SEWING MACHINE ATTACHMENT

Joseph Boruchowitz, Bronx, N. Y.

Application January 22, 1937, Serial No. 121,739

3 Claims. (Cl. 112—151)

This invention relates to sewing machine attachments. More particularly, it relates to the type of sewing machine attachment adapted for use as a gauge for rows of stitching.

5 One of the objects of my invention is to provide a sewing machine gauge of the character described, designed to quickly sew a plurality of parallel, equally spaced rows of stitching on a material in a continuous operation without the necessity of having to start each new row of stitching at the top and of breaking the thread after each row.

Another object of my invention is to provide a stitching gauge of the character described which 15 may be readily attached to any standard type of presser foot generally employed.

Still another object of my invention is to provide a double sided, symmetrically arranged stitching gauge of the character described which 20 may be used for gauging a row of stitching on either side of the needle, or on both sides at the same time, if desired.

A still further object of my invention is to provide a stitching gauge of the character described which is constructed of a single sheet of flat blanked material, which is simple in construction, which is relatively inexpensive to manufacture, which may be easily attached to and retained by the presser foot, and easily detached therefrom, which is designed to effect a marked saving of time and which at the same time operates with a high degree of efficiency for the purposes intended.

Other objects of this invention will in part be obvious and in part hereinafter pointed out.

35 The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible embodiments of this invention,

45 Fig. 1 is a plan view, partly sectional, of a stitching gauge constructed in accordance with my invention and shown in operative position, illustrating a step in the sewing of a row of stitches on a piece of material;

50 Fig. 2 is a view similar to Fig. 1 but showing a further step in the operative use of my invention, illustrating the sewing of a second row of stitches parallel to the first row;

55 Fig. 3 is a sectional view taken substantially on the line 3—3 of Fig. 2;

Fig. 4 is a bottom plan view of the device illustrated in Fig. 3;

Fig. 5 is a cross-sectional view taken substantially on the line 5—5 of Fig. 2;

60 Fig. 6 is a development view of my invention

illustrating the contour of the stamped blank;

Fig. 7 is a top plan view of a modified form of my invention; and

Fig. 8 is a perspective view of still another modified form of my invention.

In the sewing machine stitching art, it is often desired to sew a row of stitches parallel to an edge of a garment or to the edge of a piece of material. Also for decorative purposes, it is often desired to sew a plurality of equally spaced parallel rows of stitching. In the sewing of such rows of stitching, it is necessary to employ some sort of gauging means if the rows of stitching are to be straight and parallel. Heretofore, complicated and intricate gauge mechanisms were 15 employed, each of which required a specially designed presser foot for attachment. In previous gauge constructions, when it was desired during the course of the operation of the sewing machine to sew a row or rows of stitching as above 20 described, it was necessary to first remove the standard type of presser foot ordinarily used in the machine and to replace it with a specially designed presser foot which would accommodate the gauge. Another disadvantage inherent in 25 gauges or previous construction was particularly noted when it was desired to sew a plurality of rows of stitching, for then it was found that much time was lost in having to start each row of stitching at the top. This procedure also made 30 it necessary to break the thread after each row of stitching was completed.

By my invention I have provided a simple sewing machine gauge device, which is quickly attachable to any standard type of presser foot, 35 and by means of which a plurality of equally spaced parallel rows of stitching may be sewn without any of the above described disadvantages.

Referring now in detail to the drawing, there 40 is disclosed a gauge 10 constructed in accordance with my invention and shown attached to a presser foot 11 of any standard known design, having at the bottom thereof a relatively long extension 11a and a relatively short extension 45 11b, between which the needle N is adapted to pass. The gauge 10 is preferably stamped out of a single sheet of bendable metallic material in the form of a blank 12 shown in Fig. 6, comprising the substantially rectangular portions 13, 50 14 and 15, the portions 14 and 15 being interconnected with the portion 13 by a neck portion 16. To construct the gauge, the portion 15 is rolled over to form a hollow pocket member 17, which 55 may be substantially rectangular in cross section, as clearly shown in Figs. 4 and 5. The area where the portions 14 and 15 are joined, such as is indicated by the dotted line 18 of Fig. 6, is bent so as to have a rounded corner and is adapted to lie alongside a side wall 17a of the member 60

17, as shown in Fig. 5. It is noted that the portion 14 now lies in a plane parallel to and slightly above the top wall 17b of the pocket 17. The portion 13 is then folded over inwardly toward 5 the pocket 17, so that the neck portion 16 forms a wall 16a (see Fig. 3) closing off one end of the pocket 17. After folding as just described, the said portion 13 is adapted to overlie adjacent the top wall 17b of the pocket 17, said portion 13 10 then being in the same plane and in symmetrical alignment with the portion 14.

My improved gauge device as above described is designed to be attached to any standard type of presser foot 11, by having the pocket member 15 17 telescopically received on the longer extension 11a of the presser foot, as clearly shown in Figs. 1 to 5 of the drawing. The gauge 10 is held in resilient engagement on the presser foot by means of the slightly rounded corner caused 20 by bending the member 14 on the fold line 18, as previously described, because of the fact that the shorter extension 11b of the presser foot 11 is adapted to frictionally engage the underside of the portion 13 at the above mentioned area 25 18, as illustrated in Fig. 5.

It is thus seen that the gauge device may be easily and quickly attached to the presser foot and resiliently held thereon. It is noted from Fig. 4 of the drawing that the pocket member 30 17 is of lesser length than the width of the portions 13 and 14. This is designed so that the pocket member 17 will not contact the material underneath the presser foot.

The operation of my improved gauge will now 35 be described. In Figs. 1 and 2 there is shown a piece of material M on which it is desired to sew a plurality of parallel equally spaced rows of stitching. In Fig. 1 a row of stitching 20 has been started on the material M, said material moving in the direction shown by the 40 arrow, with the distance from the row of stitching 20 to the edge E of the material M being gauged by the edge A of the gauge portion 13 to provide the row of stitching 20 parallel to the edge E. When the row of stitching 20 has been completed, the material M is then turned, as shown in Fig. 2, and in a continuous sewing operation and without breaking the thread, a second row of stitching 21 is then started, sewn 45 in the opposite direction to the stitching of the row 20, but this time, since the material M has been turned around, the second row 21 is gauged on the previously made row 20 by means, this time, of the edge B of the gauge portion 14. If 50 it is desired to stitch a third parallel row to the rows 20 and 21, the same process would be repeated; that is, after the completion of the stitching of row 21, the material would be turned around again and the third row of stitching 55 20 would be gauged on the row 21 by the edge A of the gauge portion 13.

From the above described operation, the advantage of a double-sided stitching gauge, each side being the same distance, is readily seen. It 60 is also apparent that a greater saving of time is effected by my invention than the type of gauge heretofore employed, which was usually a one-sided gauge and had to be readjusted after each row of stitching, since the gauging was 65 always done from the edge of the material.

The type of double-sided gauge illustrated in Figs. 1 to 6 is adapted for the gauging of only one predetermined distance, such as $\frac{1}{4}$ ", $\frac{3}{8}$ " or $\frac{1}{2}$ ", etc., between rows of stitching. In Fig. 7, 70 however, I have shown a modified form of con-

struction of a double-sided gauge device 10', which is adaptable for more than one size. In this form, the outer gauging edges of the portions 13' and 14' are correspondingly stepped to provide different gauging distances.

In Fig. 8 I have shown still another modified form 10" of my gauge device, which is adapted for use in sewing a row of stitches parallel to a turned edge of a garment, such as an over-coat lapel, etc. and it is seen that in this case 10 the gauge portion 14" is provided with a down-turned edge 30, which is adapted to ride along the edge of the said lapel. While in this form of device, I have illustrated a single-sided gauge, since in most cases this type of gauge would be 15 used only for sewing a single line of stitching parallel to an edge, nevertheless, it is understood that the type of gauge illustrated in Fig. 8 may also be of double-sized construction similar to the gauge 10.

It will thus be seen that there is provided a device in which the several objects of this invention are achieved, and which is well adapted to meet the conditions of practical use.

As various possible embodiments might be made 25 of the above invention, and as various changes might be made in the embodiments above set forth, it is to be understood that all matter herein set forth or shown in the accompanying drawing is to be interpreted as illustrative and 30 not in a limiting sense.

Having thus described my invention, I claim as new and desire to secure by Letters Patent:

1. In combination with a sewing machine presser foot having a relatively long and a relatively short extension, a gauge member made from a flat sheet of bendable material and formed into a hollow pocket portion open at one end, and having a pair of adjacently disposed bottom walls, a pair of adjacently disposed side walls, 40 and a single end wall, a pair of flat gauge portions extending laterally from opposite sides of said pocket portion, one of said gauge portions being interconnected to the lowermost wall of said bottom walls by the outer wall of said double side wall, and the other of said gauge portions being interconnected to the lowermost wall of said bottom walls by said end wall.

2. A sewing machine gauge for gauging lines of stitching on a piece of material adapted for 50 use with a presser foot having two extensions, said gauge comprising two adjacently disposed wall portions adapted to be received in the space between said extensions and to frictionally engage the inner edges of said extensions, a pair 55 of permanently fixed gauge members integral with said wall portions and extending in opposite directions outwardly therefrom beyond the outer edges of said presser foot extensions.

3. A one-piece sewing machine gauge for gauging lines of stitching on a piece of material adapted for use with a presser foot having two extensions, said gauge comprising two adjacently disposed wall portions adapted to be received in the space between said extensions and to frictionally engage the inner edges of said extensions, a pair 60 of permanently fixed gauge members integral with said wall portions and extending in opposite directions outwardly therefrom beyond the outer edges of said presser foot extensions, said gauge members being out of contact with said material, portions of said gauge member overlying the upper surfaces of said extensions.
